UNITED STATES PATENT OFFICE.

VICENTE GUERRA Y MARRERO, OF CAIBARIEN, CUBA.

CULTIVATOR.

1,413,910.

Specification of Letters Patent. Patented Apr. 25, 1922.

Application filed August 10, 1920. Serial No. 402,673.

To all whom it may concern:

Be it known that I, VICENTE GUERRA Y MARRERO, a subject of the King of Spain, and resident of Caibarien, Apartado 161, 5 Cuba, have invented certain new and useful Improvements in Cultivators, of which the following is a specification.

This invention relates to cultivators; and its principal object, stated briefly, is to provide a machine of the character indicated 10 having improved means for operating the ground-treating devices in such a way as to cause them to travel in an elliptical path through as nearly as possible the same movements imparted to such devices when operated manually, and also having improved means for controlling the activity of the 15 clutches comprised in the operating connections between said devices and the axle, and 20 for simultaneously varying the position of the said devices with relation to the ground.

According to the invention, the ground-treating devices (which term is intended to cover both the hoes, knives or other implements which actually engage the soil and chop down the weeds, and the carrier bars or arms to which they are attached) are supported and controlled by means of connections pivotally related to an elevated, floating shaft located above the axle, and the latter is equipped with a set of cranks slidably engaged in longitudinal slots provided in certain of the connections; the arrangement being such that during the rotation of the 30 axle, the cranks operating in said slots will cause the ground-treating devices to successively advance, descend into engagement with the soil, retreat and ascend. The clutches previously referred to are operated 35 by means of flexible bars which are connected to the floating shaft and are forced inward so as to withdraw the sliding members of the clutches from engagement with the fixed members and thereby disconnect the 40 driving mechanism; and during their operation as just described, they are shifted endwise and, in consequence, move the floating shaft laterally, said shaft acting, in turn, through the previously-mentioned connections, to lift the ground-treating devices into 45 inoperative position with relation to the ground.

Other and further improvements and advantages are comprised in the invention, as 50 will presently appear; but it is to be understood that the invention is not limited to

the precise structural details of the embodiment thereof represented in the accompanying drawing, but is susceptible of modifications and changes within its scope as herein- 60 after claimed. Parts of the invention may also be utilized to the exclusion of others, and in other and different environments.

In said drawing:

Figure 1 is a plan view of the improved 65 cultivator.

Fig. 2 is a side elevation thereof.

Fig. 3 is a longitudinal vertical section on line 3—3, Fig. 1.

Fig. 4 is a transverse vertical section on 70 line 4—4, Fig. 1.

Fig. 5 is a detail view showing a modified system of connections for effecting the operation of the ground-treating devices.

Fig. 6 is a plan view of a modified form 75 of implement.

Referring more particularly to the drawing, 1 indicates the frame or chassis of the machine, the longitudinal side beams of which are provided with central bearings 80 2 wherein the main shaft or axle 3 is journaled, said axle carrying adjacent its ends the supporting or ground wheels 4 which are loosely mounted thereon. These wheels 4 have rigidly secured to them a pair of 85 sprockets 5 which are connected by chains 6 to smaller sprockets 7 loosely mounted on a cross-shaft 8 journaled in brackets 9 fixed to the rear portions of the aforesaid beams. The sprockets 7 are provided with toothed 90 hubs 10 adapted to be alternatively engaged with or disengaged from a pair of sliding clutch members 11, which are splined to shaft 8 to rotate the same when coupled to hubs 10 and which project loosely through 95 the slotted central portions 12 of a pair of spreader bars 13, the operation of the clutch members being controlled by these spreader bars in the manner subsequently explained. The rotation of shaft 8 is transmitted to 100 axle 3 by means of a large sprocket 14, connected by a chain 15 with a small sprocket 16 fixed to said axle.

The main shaft or axle 3 is provided with a set of cranks 17, disposed at suitable angles to one another and utilized to actuate the bars 18 to which the ground-treating implements 19 are attached. There are six 105 of these bars 18 in the construction illustrated (though such number, of course, is 110 purely arbitrary), arranged in three pairs; and there are four of the cranks 17, the two

central cranks being operatively associated with the two central bars, and the two outer or end cranks being each associated with the adjacent outer pair of bars, as will be seen in Fig. 1. Each crank is slidably engaged for that purpose in a longitudinal slot provided at the forward end of a rod 20, such slot being here shown as formed by a bridge-piece 21 fastened upon the upper surface of the rod, which latter is pivoted at its rear end to the lower end of a rocker arm 22. The upper end of each rocker arm is rigidly fastened to the upper end of a second rocker arm 23, the two arms 22 and 23 conjointly forming a bell-crank lever, which is loosely pivoted at its apex upon an elevated cross-shaft 24 disposed above the axle 3 and having pivoted to its opposite ends the upper or front ends of the two spreader bars 13. The rods 20 are provided at their forward ends with vertical openings, through which slide the upper ends of bolts 25, the lower ends of which slide through similar openings in the associated bars 18, the intermediate portions of the bolts being encircled by expansible coil springs 26 which bear at opposite ends against the parts 20 and 18, as shown. The front rocker arms 23 have their lower portions slotted longitudinally, as at 27, to permit the sliding engagement of the cranks 17 therein, so that the said cranks will impart rocking movements both to the bell-cranks 22-23 and to the rods 20, the latter turning about their pivotal connections with the parts 22, and the former about the elevated cross-shaft 24.

Assuming that the clutch connections are coupled up to effect rotation of the axle 3 during the forward movement of the machine, the several cranks 17 will operate to rock the bell-cranks 22-23 forward and backward, with the result that the bars 18 carrying the ground-treating implements 19 are caused to alternately advance and recede. The rods 20 are also rocked up and down by the cranks and, in turn, transmit their movements to the bars 18 and the implements 19, which latter are thereby forced to travel in a somewhat elliptical path closely resembling the movements imparted to a spade, hoe or analogous device when operated manually, the parts 19 being illustrated as hoe shaped. The springs 26 assist in the movements of the carrier bars 18 and exert a cushioning action which tends to prevent the transmission of excessive shocks, as will be understood.

The operation of the spreader bars 13 incidental to the closing and opening of the clutches, is preferably effected by a lever 28 pivoted to a bracket 29 attached to the rear beam of the chassis adjacent the driver's seat 30, said lever having associated with it a 65 detent 31 for coaction with a toothed seg-

ment 32. Lever 28 has a forwardly and downwardly inclined arm 33, whose lower portion is slotted longitudinally as at 34; and through this slot passes a horizontal cross-bar 35 which is attached at its ends to 70 the adjacent portions 36 of the spreader bars, the arrangement being such, therefore, that when said lever is rocked in one direction or the other about its pivot, the cross-bar 35 will be shifted laterally by the 75 lever arm 33 and, in consequence, will impart an endwise movement to the spreader bars. The movement of the spreader bars will be transmitted, in turn, to the floating cross-shaft 24, with the result that the bell- 80 cranks 22-23 will be shifted to one side or the other and, through the intermediary of their connections with the hoe bars 18, will move the latter toward or from the ground. The portions 36 of the spreader 85 bars converge, as shown in Fig. 1, and terminate adjacent a pair of depending posts 37 fastened to the rear beam of the chassis; from which it follows that when the spreader bars are forced rearward, their inclined portions 36 will engage said posts and will be pressed or cammed inwardly toward each other, said bars being sufficiently thin and resilient to permit them to flex and so perform the movement in question. During 95 this movement, the walls of the slotted portions 12 of the bars will engage the collars 38 provided on the inner ends of the clutch sleeves 11 and, as the movement continues, will shift said sleeves inwardly along shaft 100 8, thus uncoupling them from the clutch hubs 10 on the sprockets 7, so that the rotation of said shaft and, hence, of axle 3, will thereupon cease. Movement of the controlling lever 28 in the opposite direction will, 105 of course, effect a forward movement of the spreader bars, which latter will tend to expand or move outwardly away from each other, due to their resiliency, as their inclined or cam portions 36 pass across the 110 posts 37; the forward movement of the spreader bars producing a lowering of the hoe bars and their hoes toward the ground. The clutch sleeves 11 are automatically coupled with the clutch hubs 10, as the spreader 115 bars advance, by means of expansible coil springs 39 interposed between the collars 38 and the sprocket 14 and encircling the shaft 8.

The machine may be drawn over the 120 ground by draft animals hitched to a pair of shafts 40 connected to the front beam of the chassis (which shafts, if preferred, may be replaced by a single pole or tongue), or it may be propelled mechanically by means 125 of a suitable motor and driving connections (not shown), according as may be desired.

In Fig. 5 there is represented a slightly modified arrangement which may be substituted for the bell-cranks 22-23, the bars 130

20 and their bridges 21 and the spring-controlled bolts 25. According to this arrangement, the bell-crank are replaced by rocker arms or levers 41, which are pivoted at their 5 upper ends to the elevated shaft 24 and are formed with vertical slots or channels 42, each having a cross-pin 43 spanning it. The hoe-carrying bars 44 are pivoted at their rear ends to the lower ends of the rockers 41 and are formed with longitudinal slots 45 in which travel lateral pins or rollers 46 attached to the lower ends of a set of floating links 47, one for each carrier bar. These 10 links 47 are formed with longitudinal slots 15 48 in which are engaged both the cross-pins 43 and the axle cranks 17. Rotation of the axle will, therefore, cause the hoe bars to travel in elliptical paths similar to those of the bars 18; the rockers or levers 41 swinging 20 forward and backward and thereby imparting corresponding endwise movements to the hoe bars 44 which are also raised and lowered due to the travel of the rollers 46 in slots 45. The above-mentioned rocking 25 movements of the parts 41 are produced, of course, by the engagement of the cranks 17 in slots 48, in which latter the cross-pins in the slots 42 are also engaged.

Fig. 6 represents a modified form of 30 ground-treating implement comprising a flat, substantially-rectangular blade 49 formed with a central longitudinal guide rib 50 which fits slidably in a longitudinal groove 51 provided in a T-shaped member 35 52. The cross-piece of the latter has pivoted to its opposite ends a pair of flat, angular members 53 whose long, lower arms converge and whose shorter or upper arms are slidably connected with the carrier bars 18 or 40 44. Grapples or anchors 54 may be attached to the carrier bars to adjust the position of the ground-treating implements in conformity with the widths of the furrows being dug.

I claim as my invention:—

- 45 1. In a cultivator, the combination of a chassis; supporting wheels therefor; an axle journaled in the chassis and whereon said wheels are mounted; a set of ground-treating devices; an elevated cross-shaft; supporting connections for said ground-treating devices pivotally related to said shaft and comprising members provided with longitudinal slots; and a set of cranks on said axle slidably engaged in said slots for causing 50 the ground-treating devices to travel in an elliptical path when the axle is in motion.
- 55 2. In a cultivator, the combination of a chassis; supporting wheels therefor; an axle journaled in the chassis and whereon said wheels are mounted; an elevated cross-shaft; a set of bell-crank pivots therefrom at their apices, one arm of each bell-crank being longitudinally slotted; a ground-treating device pivoted to the other 60 arm of each bell-crank; a rod operatively re-
- lated to each ground-treating device and having a longitudinal slot; and a set of cranks on said axle slidably engaged in both the first-named and the second-named slots, so as to cause the ground-treating devices 70 to travel in an elliptical path when the axle is in motion.
3. In a cultivator, the combination of a chassis; supporting wheels therefor; an axle journaled in the chassis and whereon said 75 wheels are mounted; an elevated cross-shaft; a set of bell-crank pivots therefrom at their apices, one arm of each bell-crank being longitudinally slotted; a ground-treating device pivoted to the lower 80 end of the other arm of each bell-crank; a rod pivoted to the said lower end of each second-named bell-crank arm and provided with a longitudinal slot; a cushioning device slidably engaged at opposite ends with each 85 of said rods and the associated ground-treating device; and a set of cranks on said axle slidably engaged in both the first-named and the second-named slots, so as to cause the 90 ground-treating devices to travel in an elliptical path when the axle is in motion.
4. In a cultivator, the combination of a chassis; supporting wheels therefor; an axle journaled in the chassis and whereon said 95 wheels are mounted; a set of ground-treating devices; means associated with each ground-treating device for guiding and controlling its movements, each of said means comprising an element having a longitudinal slot; and a set of cranks on said axle slidably engaged in said slots to operate the 100 guiding and controlling means and thereby cause the ground-treating devices to travel in an elliptical path when the axle is in motion.
5. In a cultivator, the combination of a chassis; supporting wheels therefor; an axle journaled in the chassis and whereon said 105 wheels are loosely mounted; mechanism, including clutching means, for connecting said wheels with said axle to rotate the same; a set of ground-treating devices; means operated by the axle for actuating them; and means for simultaneously controlling the activity of the clutching means and the position of the ground-treating devices.
6. In a cultivator, the combination of a chassis; supporting wheels therefor; an axle journaled in the chassis and whereon said 110 wheels are loosely mounted; mechanism, including clutching means, for connecting said wheels with said axle to rotate the same; a set of ground-treating devices; means operated by the axle for actuating them; and means for simultaneously uncoupling the 115 clutching means and shifting the ground-treating devices into inoperative position with relation to the ground.
7. In a cultivator, the combination of a chassis; supporting wheels therefor; an axle 120
- 65 130

- 1   journaled in the chassis and whereon said wheels are loosely mounted; mechanism, including clutch means, for connecting said wheels with said axle to rotate the same; a set of ground-treating devices; means operated by the axle for actuating them; and a cam mechanism for simultaneously controlling the activity of the clutching means and the position of the ground-treating devices.
- 10   8. In a cultivator, the combination of a chassis; supporting wheels therefor; an axle journaled in the chassis and whereon said wheels are loosely mounted; mechanism, including clutching means, for connecting said wheels with said axle to rotate the same; a set of ground-treating devices, means operated by the axle for actuating them; an elevated shaft; supporting connections for the ground-treating devices suspended from said shaft; and means for simultaneously operating the clutching means and shifting said shaft laterally to vary the position of the ground-treating devices with relation to the ground.
- 15   9. In a cultivator, the combination of a chassis; supporting wheels therefor; an axle journaled in the chassis and whereon said wheels are loosely mounted; mechanism, including clutching means, for connecting said wheels with said axle to rotate the same; a set of ground-treating devices, means operated by the axle for actuating them; an elevated shaft; supporting connections for the ground-treating devices suspended from said shaft; a pair of spreader bars for controlling the activity of the clutching means connected with said shaft; and operating means for the spreader bars adapted to force them inward toward each other and to simultaneously move them endwise, thereby to simultaneously open the clutching means and shift said shaft laterally to vary the position of the ground-treating devices with relation to the ground.
- 20   10. In a cultivator, the combination of a chassis; supporting wheels therefor; an axle journaled in the chassis and whereon said wheels are loosely mounted; mechanism, including clutching means, for connecting said wheels with said axle to rotate the same; a set of ground-treating devices; means operated by the axle for actuating them; an ele- 45 vated shaft; supporting connections for the ground-treating devices suspended from said shaft; a pair of spreader bars for controlling the activity of the clutching means connected with said shaft; and operating means for the spreader bars adapted to force them inward toward each other and to simultaneously move them endwise, thereby to simultaneously open the clutching means and shift said shaft laterally to vary the position of the ground-treating devices with relation to the ground.
- 25   11. In a cultivator, the combination of a chassis; supporting wheels therefor; an axle journaled in the chassis and whereon said wheels are loosely mounted; mechanism, including clutching means, for connecting said wheels with said axle to rotate the same; a set of ground-treating devices, means operated by the axle for actuating them; an ele- 50 vated shaft; supporting connections for the ground-treating devices suspended from said shaft; a pair of spreader bars for controlling the activity of the clutching means connected with said shaft; and operating means for the spreader bars adapted to force them inward toward each other and to simultaneously move them endwise, thereby to simultaneously open the clutching means and shift said shaft laterally to vary the position of the ground-treating devices with relation to the ground.
- 30   12. In a cultivator, the combination of a chassis; supporting wheels therefor; an axle journaled in the chassis and whereon said wheels are loosely mounted; mechanism, including clutching means, for connecting said wheels with said axle to rotate the same; a set of ground-treating devices, means operated by the axle for actuating them; an elevated shaft; supporting connections for the

Signed at Habana, Cuba, this 3rd day of August, A. D. 1920.

VICENTE GUERRA Y MARRERO.
